UNITED STATES PATENT OFFICE.

VIOLA ROOT CAMERON, OF NEW YORK, N. Y.

FUEL-CHARGE-TREATING DEVICE.

Original application filed October 12, 1922, Serial No. 594,216. Divided and this application filed November 16, 1922. Serial No. 601,282.

To all whom it may concern:

Be it known that I, VIOLA ROOT CAMERON, a citizen of the United States, residing at New York, in the county of New York 5 and State of New York, have invented new and useful Improvements in Fuel-Charge-Treating Devices, of which the following is a specification.

This invention relates to gas saving devices for internal combustion engines, and pertains particularly to devices for breaking up and mixing combustible charges of fuel and air.

This invention is an improvement on the 15 type of gas saving device described in the patent to Lampert, 1,192,435, issued July 25, 1916, which patent provides for an article to be inserted between a carbureter and the intake ports of an engine, the device including a metal plate member having a coiled spring cone mounted over an opening in the plate member, and having its base coil fixed to the plate member, the remainder 20 of the cone being unattached and free to vibrate. In the Lampert device, the plate is of solid material; has the general contour of a gasket; and is used between adjacent flanges of pipe ends. The metal wall of the opening in the Lampert device is provided with an annular groove to receive and hold, by the expansive spring action, 25 the largest or base coil of the spring cone.

The general object of the present invention is to improve on the Lampert type of 30 device, and at the same time, retain the advantageous features of the freely vibratile spring cone.

One of the features of the invention relates to the improved means for so securing 35 the base coil of the spring wire to the supporting plate that the coil cannot be loosened or separated accidentally from the supporting plate, due to the vibrations of the spring or the jolting or vibration of the engine.

Another feature is the combination of 40 the spiral spring with the standard asbestos copper gasket, supplemented and modified by the particular fastening means for holding the spring over the gasket opening.

Another feature is directed to the particular shape and mounting of the spiral 45 spring cone, which may be compressed to occupy the space of the thickness of the gasket or plate in the opening of which it is mounted. This design makes it possible

to insert the plate or gasket and spring sidewise into position between adjacent pipe ends without necessitating the wide separation of the connection, it being merely necessary to loosen the connection sufficiently 50 wide to insert the thickness of the plate or gasket. After such insertion, the spring cone is then free to assume its normal conical shape, and to serve in breaking up the incoming charge of the fuel mixture. This 55 feature is particularly important because of the ease by which the device may be installed. By using an asbestos copper gasket of ordinary thickness, and having the cross-sectional diameter of the material 60 of the spring no greater than the thickness of the gasket, the device may readily be inserted in any engine intake line without requiring modification of the engine parts.

The device of the present invention may 65 be inserted at any connection between the carbureter and the inlet ports. Satisfactory locations have been at the engine and at the carbureter ends of the intake manifold. The apex of the cone may extend in either direction, 70 according to convenience, provided it does not interfere with the engine parts.

The above and other features and advantages of the device of the invention will 75 be described and claimed in the following 80 specification and claims, and illustrated in the accompanying drawing, in which:

Figure 1 represents a sectional view of 85 the combined asbestos copper gasket and spring, in which one face of the metal portion of the asbestos copper gasket projects centrally and then axially through the opening and is recurved about the largest coil 90 of the spring and alongside of the opposite face of the gasket;

Figure 2 represents a top plan view of 95 the gasket and retaining ring, as shown in Figure 1, but with the spring removed;

Figure 3 represents, in section a modification of the form illustrated in Figure 1, 100 the spring retaining means being formed of a plurality of eyelets, struck up from the material of one face;

Figure 4 shows, in section, the gasket 105 illustrated in Figure 1, but with the conical spring compressed into the plane of the gasket, illustrating the compressed position in which the device is adapted to be inserted between adjacent pipe and flanges;

Figure 5 represents a top plan view of 110

the asbestos copper gasket, shown in Figure 3, illustrating one of the eyelets projecting centrally prior to being recurved about the largest coil of the spring member; and

5 Figure 6 represents a top plan view of the conical spiral spring removed from the gasket and retaining member.

Referring in detail to the various figures of the drawings, like numerals refer to like 10 parts in the different figures.

1 is a spiral spring member formed in the shape of a cone, and so designed that it may be compressed to a plane having the thickness of a cross-section of the material 15 of the wire, as illustrated in Figure 4. The apex of the cone is indicated at 1^a. The base of the cone is formed by the largest coil or turn of the spring wire and is indicated at 1^b. 2 represents a gasket member or 20 plate upon which the spring 1 is mounted, and which serves to hold the spring in its operative position when installed in the intake line of an internal combustion engine. 3 is a central opening in the member 2, and 25 4 indicates end slots or openings for the reception of fastening bolts or studs by which the member 2 and its adjacent pipe connections are secured together. The spring 1 is held in its mounted position with the axis 30 of the cone in line with the axial center of the opening 3, and accordingly, the largest coil 1^b is held adjacent to the wall of the opening 3, or actually in the same plane with the wall of the opening.

35 The invention provides several different specific constructions for securely holding the coil 1^b in its position about the opening 3. In the sectional views of the drawing, the upper face of the gasket member is indicated at 2^a and the lower face is indicated at 2^b, and the asbestos intermediate portion of the gasket is indicated at 2^c. The asbestos portion 2^c may be cut back away from the central opening thus providing an annular space between the faces 2^a and 2^b, as indicated at 5. The largest coil of the conical spring 1 is shown held in this annular space by its spring action, which tends to expand the lower coil 1^b against the material 2^c. Thus, the spring is held by the material 2^c laterally, and by the opposite metal material 2^a and 2^b on the top and bottom, in addition to the particular retaining member which will be described.

50 In the views illustrated in Figures 1, 2 and 4, the retaining element 6 is formed by an extension of the under face of the copper portion of the gasket, which will be seen as extending centrally, thence through the opening, and thence being received along side of the opposite face 2^a.

55 In each of Figures 1, 2 and 4, an opening 7 will be seen, through which the upwardly extending spring projects. The opening 7 is preferably elongated in order to prevent

undue distortion of the curvature of the spiral spring. It is desirable also that the opening 7 extend through the thickness of the member 6, sufficiently deeply so that the coil of the spring projecting through the opening may be compressed to the plane of the gasket, as in Figure 4.

In the modification illustrated in Figures 3 and 5, the under face of the copper portion of the gasket is extended inwardly to form 75 a plurality of eyelets 8 adapted to be curved upwardly through the opening 3 and thence along side of the opposite face of the gasket. This arrangement is substantially similar to the arrangement illustrated in 80 Figures 1, 2 and 4 except that the eyelets are formed separately instead of as one continuous portion. In Figure 5, the length of one eyelet member is shown as fully extended centrally, and prior to the recurring 85 of it into the eyelet shape.

It is intended that the end of the larger coil of the spring cone be inserted into the opening 7 and the coil and gasket rotated with respect to each other, so as to thread 90 the largest coil 1^b into and around through the space provided by the fastening member 6, the side faces 2^a and 2^b of the gasket and the asbestos material 2^c. In the form shown in Figures 3 and 5, the eyelet members may 95 be bent up and recurved around the largest coil 1^b of the wire, or the end of the largest coil may be threaded through the plurality of eyelets in substantially the same manner as provided for in Figures 1, 2 and 4.

100 For the insertion of the combined spring and gasket into position in an internal combustion engine, the invention contemplates the use of any necessary device, such as a pair of pliers, by which the spring may be 105 compressed to the thickness of the material of the gasket by the same movement and by the same position of the implement which the operator uses in holding the gasket. If the place of installation be readily accessible, and the spring readily compressible, the operator may use his fingers in compressing the spring and slipping the device 110 sidewise, or edgewise, in between the adjacent pipe ends.

115 The curvature of the spirals of the spring should be so arranged that a line drawn through the material of the spring at any point and parallel to the axis of the cone will not pass through the material of the 120 next adjacent turn or coil of the spring, or any other portion of the spring. This description is presented as one way of stating that the conical spring may be compressed to a given plane without distorting any of 125 the turns or coils of the spring in order to assume the plane position.

This application is specifically directed to that form of the invention in which the material of one face of the gasket is ex- 130

tended and used as the spring holding member. Claims to the use of a separate part are presented in my copending application Serial No. 594,216, filed October 12, 5 1922, from which this application has been divided. Specific claims to the spiral spring are presented in my copending application Serial No. 601,283, filed November 16, 1923.

10 What I claim is:

1. In a device of the character described, a plate member having an opening therethrough, a coiled spring cone having the base thereof positioned in said opening and 15 freely vibratile from the base to and including the apex of the cone, and fastening means comprising a continuation of the material of one face of said plate member engaging the base portion of said cone on 20 the side thereof opposite to the encircling wall of said opening and holding said cone in axial alignment with said opening.

2. In a device of the character described, a plate member having an opening therethrough, a coiled spring positioned in line with said opening, and fastening means comprising a continuation of the material of one face of said plate member engaging the axial side of the coil 30 of said spring next adjacent the wall of said opening and holding said spring in position, said spring being freely vibratile from the supported portion thereof next adjacent the wall of said opening to and 35 including the opposite end of said spring.

3. In a device of the character described, a plate member having an opening therethrough, a coiled spring cone positioned in line with said opening, and fastening means 40 comprising a continuation of the material of one face of said plate member engaging the coil of said spring cone next adjacent the wall of said opening and supporting said

coil on the axial side thereof, said spring cone being freely vibratile from the supported portion thereof next adjacent the wall of said opening to and including the opposite end of said spring cone. 45

4. In a device of the character described, a gasket comprising opposite outer metal 50 faces and an intermediate material therebetween and having an opening through the thickness of the gasket, a coiled spring having the largest coil thereof fitted concentric with the wall of said opening, and an extension of one face of said gasket extending centrally, thence axially of said largest coil and thence recurved toward said opposite gasket face, providing an outer annular groove the side walls of which embrace said 55 largest coil and the adjacent portions of said opposite gasket faces, said spring being freely vibratile from the supported portion thereof next adjacent the wall of said opening to and including the opposite end of 60 65 said spring.

5. In a device of the character described, a gasket comprising opposite outer metal faces and an intermediate material therebetween and having an opening through 70 the thickness of the gasket, a coiled spring having the largest coil thereof fitted concentric with the wall of said opening, and a plurality of eyelets each formed as an extension of one gasket face, each eyelet extending centrally, thence axially of said largest coil and thence recurved toward said opposite gasket face, said largest coil being threaded through said plurality of eyelets, and said spring being freely vibratile from 75 80 the largest coil thereof to and including the opposite end of said spring.

In testimony whereof I affix my signature.

VIOLA ROOT CAMERON.
